FIRE RESISTANT CLOSURE FOR PASSAGEWAYS

William A. Bear, % Bear Coal Co.,
Somerset, Colo. 81434
Filed Feb. 28, 1964, Ser. No. 348,177
8 Claims. (Cl. 52—98)

The present invention generally relates to a fire resistant closure for passageways and while the invention is specifically adapted for use in coal mines, it will have other uses and applications wherein a fire resistant closure is desirable.

In mining operations and especially in coal mines, certain tunnels, cross-cuts and other passageways must be closed in an air-tight manner to control the flow of air for safety purposes in removing harmful gases and for providing fresh air as well as for fire control. In present procedures, this air-tight closure is often accomplished by building masonry walls similar to those used in building structures. It will be appreciated that the building of such a masonry wall is quite time-consuming and requires the services of a mason and also requires that the building material for the wall be conveyed to the point of construction of the air-tight closure which requires considerable time and effort.

Accordingly, it is an object of the present invention to provide a fire resistant closure for underground passageways such as tunnels, cross-cuts and the like appearing in a coal mine or any other mine which is constructed of a fabricated metal framework having fire resistant material mounted thereon so that the framework components may be standard manufactured articles thereby reducing the cost of assembly and enabling assembly in a shop or other area located above ground.

Another objection to the masonry wall for forming a closure for a mine passageway is the fact that such a closure is substantially permanent in that the wall or closure cannot be removed except by using implements normally employed for tearing down a masonry wall. Therefore, it is a further object of the present invention to provide a fire resistant closure including stripping means incorporated therein for enabling the fire-resistant closure to be easily removed by miners or the like when desired or necessary such as in an emergency condition such as when endeavoring to escape from one tunnel into another in the event of an explosion, accumulation of gas or the like.

Still another object of the present invention is to provide a fire resistant closure that may be equipped with anchoring prongs in order to hold the closure in position in the passageway thereby enabling the closure to be set up securely without waiting for mortar to dry such as occurs in constructing a masonry wall. Also, when the closure of the present invention is removed, the components thereof may be re-used whereas a masonry structure when it is broken up cannot be re-used.

A further object of the present invention is to provide a fire resistant closure for the ground passageways having a prefabricated frame structure with screen paneling and a foam plastic material applied thereto which is fire resistant and also capable of being sealed around the edges of the passageway by spraying the foam material into any opening around the periphery of the closure due to irregularities in the surface of the passageway.

Still another object of the present invention is to provide a fire resistant closure which is rather simple in construction, easy to install, advantageous as compared with a conventional masonry wall and relatively inexpensive to manufacture.

These together with other objects and advantages which will become subsequently apparent reside in the details of construction and operation as more fully hereinafter

2

described and claimed, reference being had to the accompanying drawings forming a part hereof, wherein like numerals refer to like parts throughout, and in which:

- 5 FIGURE 1 is an elevational view of the fire resistant closure of the present invention installed in an underground passageway;
- 10 FIGURE 2 is a top plan view of the construction of FIGURE 1;
- 15 FIGURE 3 is a detailed elevational view of the fire resistant closure with the layered components thereof broken away for illustrating the construction of the framework, the screen paneling and the foam material thereof;
- 20 FIGURE 4 is a vertical, sectional view, on an enlarged scale, taken substantially upon a plane passing along section line 4—4 of FIGURE 1 illustrating further structural details of the fire resistant closure of the present invention;
- 25 FIGURE 5 is a detailed sectional view, on an enlarged scale, taken substantially upon a plane passing along section line 5—5 of FIGURE 3 illustrating further structural details of the invention;
- 30 FIGURE 6 is an elevational view, portions broken away, illustrating another embodiment of the invention orientated in an irregularly shaped passageway;
- 35 FIGURE 7 is an elevational view illustrating another embodiment of the invention with portions thereof broken away illustrating the manner in which a door may be incorporated into the fire resistant closure;
- 40 FIGURE 8 is a fragmental perspective view of one corner of a framework illustrating the manner in which prongs may be used for securing the closure in place;
- 45 FIGURE 9 is a plan view of a closure assembly illustrating the manner in which the panels thereof may be overlapped for forming a complete closure for the passageway;
- 50 FIGURE 10 is a perspective view illustrating a pre-fabricated panel such as used in the assembly of FIGURE 9;
- 55 FIGURE 11 is a perspective view illustrating the manner of forming the panel of FIGURE 10;
- 60 FIGURE 12 is a sectional view taken substantially upon a plane passing along section line 12—12 of FIGURE 11 illustrating further structural details of the manner of forming the panel of FIGURE 10;
- 65 FIGURE 13 illustrates one form of connecting means between components of the framework for enabling adjustment and dismantling thereof;
- 70 FIGURE 14 is a perspective view of the fastener employed in FIGURE 13; and
- 75 FIGURE 15 is a fragmental perspective view illustrating one manner of forming fastener elements on the framework for suspending the screen paneling therefrom.
- 80 Referring now specifically to the drawings, the numeral 10 generally designates the closure of the present invention installed in a cross-cut passageway 12 interconnecting tunnels 14 for forming a closure for the passageway 12. The passageway 12 is substantially rectangular in configuration and the fire resistant closure 10 includes an adjustable rectangular framework 16 including longitudinally adjustable end members 18 and longitudinally adjustable longitudinal members 20. Each of the end members 18 are constructed of a pair of angle iron members 22 and 24 each of which is provided with a plurality of longitudinally spaced apertures 26 therein by virtue of which the overlapping ends thereof may be secured adjustably together by a pair of fastening members 28 which may be conveniently nut and bolts or the like. As illustrated, the apertures 26 in one of the members 22 are slightly elongated longitudinally while the apertures 26 in the other of the members 24 are slightly elongated trans-

versely thus enabling a certain degree of misalignment of the angle iron members 22 and 24 in order to conform the end members 18 to the side walls of the passageway 12.

The longitudinal rails or members 20 are also constructed of a pair of angle iron members 30 and 32 which overlap in the same adjustable manner with each of the members being provided with apertures 34 for receiving fasteners 36 with the apertures 34 being orientated in the same manner as in the end member 18. The upper and lower longitudinal members 20 are secured to the end members 18 by fastening bolts 38 at the ends of the end members 18 and an intermediate longitudinal member 20 is secured adjustably to either of the sections 24 or 22 by a suitable fastening bolt 40.

For anchoring the frame 16 to the top and bottom wall of the passageway, anchoring elements 42 are inserted through apertures provided in the horizontal flanges of the sections of the longitudinal members 20. The anchoring members 42 may be any suitable type of expansion device which may be driven into the top wall of the passageway or it may be the type of device that requires a pre-drilled hole.

Attached to the vertical or outer flange of the angle iron members 30 and 32 which forms the top longitudinal member 20 is a plurality of generally L-shaped hooks 44 secured rigidly to the flange of the angle iron members 30 and 32 as illustrated in FIGURE 4. A screen paneling 46 of reticulated screen material is supported from the framework by engaging over the hooks 44 as illustrated in FIGURE 4 thereby detachably supporting the screen panels 46 on the framework 16.

Mounted on and impregnated through the openings of the screen panels 46 is a coating or layer of foamed plastic material 48 which is fire resistant and which forms a complete closure for the screen panelings 46 and the framework 16. The foam plastic 48 is sprayed on and around the edges of the framework between the irregularities in the passageway 12 and the framework 16, the foam plastic is sprayed into the openings as indicated by numeral 50 in FIGURE 4 thus completely sealing in an air-tight manner the passageway 12. The foam plastic material is sprayed in place by conventional methods and any suitable foam plastic having fire resistant properties may be employed. One example of such foam which may be effectively employed is sold under the name of "Rigid Foam" by Mine Safety Appliance Company.

With the layer of foam plastic material laminated to the screen paneling 16, a continuous monolithic closure is provided for the passageway 12. Incorporated into the structure is a means for enabling removal thereof and this means includes a plurality of stripping wires 52 which are embedded in the foam plastic material immediately adjacent the surface of the screen paneling 46 as illustrated in FIGURE 4 and also in FIGURE 5. The top end of the stripping wire 52 projects forwardly from the face of the foam material 48 so that by gripping the free end thereof, the stripping wire may be pulled downwardly thus forming a kerf or groove substantially completely through the foam plastic material whereby the screen paneling 46 may then be removed by lifting it upwardly off of the hooks 44 thereby enabling the closure to be removed in the event of an emergency or in the event it is desired to remove the closure for any reason whatsoever. The bottom ends of the stripping wire 52 are fastened to the screen panels by twisting the wire thereto at the bottom edge of the screen panel. It is pointed out that the stripping wire 52 must be lined up with the edges of the screen wire panel so that they coincide whereby the foam will be completely cut through when the stripping wire is pulled at the loose end thus breaking the bond at the panel joints so that the panels may be removed and salvaged when changing air stops and in case of an emergency a trapped miner can pull a few wires, remove the panels and escape providing he

is on the foam side of the closure. If trapped on the frame side of the closure, he merely kicks the panels apart by kicking at the screen panels near a juncture between the panels.

As will be apparent, the framework is constructed of readily available structural components which may be easily transported to the site of the closure and erected using conventional erecting procedures with no particular skills required for installing the closure panel. After the framework has been set up, the screen panels may be easily assembled thereon and the stripping wires orientated in proper position and the foam material sprayed thereon in a conventional manner thus forming a complete air-tight closure for the passageway 12 in a relatively short time and using relatively unskilled labor and enabling the dismantling of the closure for re-use of the components when desired and enabling emergency exit of a trapped miner or the like in the event it becomes necessary to remove the closure for this purpose.

FIGURES 6 and 7 illustrate other types of installations which may be employed. FIGURE 6 illustrates a generally trapezoidal arrangement including a framework 54 which may be constructed in the same general manner as the above invention but with the lower longitudinal frame member being longer than the intermediate longitudinal frame member and the upper longitudinal frame member thus enabling one of the end frame members 56 to be orientated in an angular relation or inclined relation to conform generally to the surface of the passageway 58. In this form of the invention, the screen panels 60 are applied in the same manner with one of the screen panels being of irregular shape to completely overlie the framework 54 and the stripping wires are applied in the same manner along with the foam plastic material.

FIGURE 7, the framework 62 is constructed of conventional angle iron components and includes a door frame structure receiving and pivotally supporting a door 64 that is constructed of the same type of components as employed in the framework and supported from the door frame by hinges 66 and a suitable handle 68 is provided for enabling the door to be opened and closed when desired. In this construction, the door as well as the framework is provided with screen paneling 68 of overlapping sections and the foam plastic covers a screen panelling on the door as well as the screen paneling on the framework 62 thus providing a closure panel having an access door therethrough which may be secured in closed position by any suitable means. Stripping wires are provided in this construction in the same manner as in the construction of FIGURES 1-4 inasmuch as there is a possibility that the door will become jammed and it may become necessary to have an emergency exit alongside of the door which may be accomplished by pulling the stripping wire in the manner described hereinbefore. Further, the stripping wires enables the screen panels and the foam plastic thereon to be removed for dismantling so that they can be re-used later on.

FIGURE 8 illustrates a framework 70 having an anchor means 72 connected thereto in the form of an elongated rod 74 having an L-shaped bracket 76 attached to the corner of the framework 70 by fastening bolts 78 or the like. The rod 74 is welded in place as at 80 in perpendicular relation to the framework 70 and the ends of the rod 74 each are upturned and provided with pointed terminal ends 82 for forming prongs for anchoring the framework 70 to the peripheral surface of the passageway. The rod 74 provides resiliency to the anchor prongs and the prongs serve as supports for the framework thereby eliminating the necessity of using the roof and floor anchors illustrated in FIGURES 1-5.

FIGURES 9-12 disclose another type of closure generally designated by numeral 84 orientated in a passageway 86. In this form of the invention, a plurality of prefabricated panels generally designated by 88 are employed and are mounted on a framework 90 which in-

cludes overlapping adjustable longitudinal frame members 92 and overlapping adjustable end frame members 94 with their being provided supporting hooks or the like on the vertical flange of the uppermost longitudinal frame member 92. Each of the prefabricated panels 88 includes a screen panelling member 96 generally equivalent to the screen panels 46 employed in FIGURES 1-5. Applied to the screen panelling 96 is a layer of foam plastic material 98 equivalent to the foam plastic material 48 employed in FIGURES 1-5. Also incorporated into the foam plastic material 98 is a stripping wire 100 that is embedded in the foam plastic material closely adjacent the screen panelling 96 and closely adjacent one edge thereof. The panels 88 are prefabricated and each of the panels 88 have a portion of the screen panel 96 projecting laterally of the plastic material 98 so that this flange or portion of the screen panel 96 may overlap under an adjacent edge of an adjacent panel 88 thus forming an overlapping connection between the prefabricated panel 88 as illustrated in FIGURE 9. The joints between the panels 88 may be filled with a foam plastic material 102 as illustrated in FIGURE 9 and the space between the periphery of the closure 84 and the passageway 86 may also be filled with foam plastic 104 thus forming a complete closure. In this form of the invention, the panels are prefabricated and the frame 90 is installed and the panels merely hung in place thereon from the topmost longitudinal frame members and with the panels 88 in overlapping relation. Then, the joints 102 are sealed with the foam plastic 102 and the periphery of the closure is sealed by the foam plastic 104 thus forming a quickly assembled closure and also provided an arrangement in which the panels may be readily disassembled by employing the stripping wire which due to its close proximity to the edge of the foam plastic 98 having the seal foam plastic 102 engaged therewith will break the bond between the adjacent panel 88 by cutting through a very small portion of the foam plastic 98 and also the foam plastic 102 thereby breaking the bond between the panels 88 so that they may be removed to enable dismantling of the closure for re-use for the stripping wires enabling dismantling of the panels 88 to enable passage through the passageway 86 in the event of an emergency.

FIGURES 11 and 12 illustrate a structure for forming the prefabricated panels 88 and include a supporting plate 106 having a narrow plate 108 attached to one edge thereof by hinges 110. The plate 106 supports the screen panelling 96 with the pivot plate 108 overlying a portion of the edge thereof for clamping the screen panel 96 in place and also forming a protector for the area of the screen panel 86 which will not be covered with the foam plastic 98. One end of the plate 106 is provided with a bracket 112 having a notch 114 therein which receives one end of the stripping wire 100. The other end of the stripping wire is anchored to the screen panel 96 at the opposite end thereof. After the screen panel 96 has been assembled on the supporting plate 106 and the stripping wire 100 orientated therein, the foam plastic 98 is applied and allowed to harden. Spacer blocks 116 are provided along the edge of the plate 106 having the hinges 110 for properly orientating the screen panel 96 in relation to the supporting plate 106. The top surface of the plate 106 which may be wood or metal, is provided with a covering of plastic sheeting 118 such as polyethylene or the like in order to prevent adhesion of the foam to the top surface of the supporting plate 106.

The prefabricated panels 88 are formed above ground outside of the mine and enables the relatively inexpensive production of such panels and then conveyance of the panels to an underground location thereby requiring only the installation of a framework using conventional structural components at the underground site thereby reducing the cost of the closure member and enable installation thereof with relatively unskilled labor.

FIGURES 13 and 14 illustrate a manner of securing

the frame members together including fastener elements 120 having tapered ends 122 for centering the aligned apertures in frame sections 124 and 126. Each of the fasteners 120 is provided with a slot-like aperture 128 extending therethrough for receiving a wedge-type securing element 130 which will serve not only to clamp the frame members 124 and 126 together but also serves to frictionally anchor itself in place as illustrated in FIGURE 13.

FIGURE 14 illustrates a frame member 132 having a vertical flange 134 with an outwardly struck upwardly inclined lug 136 which forms a hook for supporting the screen panels which represents an optional manner of forming the supporting hooks for the screen panels along the top frame member of the closure.

The structural elements may be angle iron or other suitable shapes and may be constructed of standard steel or aluminum structural sections or it may be formed from steel or aluminum flat strips. Aluminum is used where the structures are to be handled frequently in order to lessen the work load in installing them. As pointed out, the structural shape of the various frame members may be varied as long as they have sufficient structural strength and of a shape necessary to adapt itself to the conditions encountered as well as to the size of the openings. The supporting frame work is adjustable so that it may be worked into a variety of shapes to conform to the configuration of the passageway by lengthening or shortening the members as desired. The hooks for supporting the screen panels may be stamped, welded or riveted into place and in lieu of the bolt type connectors, various connectors may be employed for securing the structural components in adjusted position. For example, the fastener structure illustrated in FIGURES 13 and 14 may be employed as well as other types of fasteners. By using various structural elements, the shape of the closure member may be varied to conform with various irregular passageway shapes and the structural pieces can be bent to make curved edges and could be constructed to close off the completely round or oval-shaped tunnel if desired. In addition, panels can be assembled in such a manner in an open space so as to form four walls and a top thus making a fire resistant room.

As the foam is sprayed onto the screen panels or sprayed to seal the prefabricated panels, the voids between the peripheral wall and the interior surface of the passageway is effectively sealed as the foam expands and hardens. Where access is maintained through the fire resistant closure for purposes of inspection, maintenance, escape-ways or the like, the arrangement in which a door is installed may be provided. The anchoring prongs may be used when roof bolts cannot be used and the anchoring prongs are used on the four corners of the framework and, if necessary, they can be used at spaced points across the top and bottom members but in this case they should have vertical frame members aligned therewith to hold the prong members securely against the coal or rock. Due to the construction of the prongs and brackets illustrated in FIGURE 8, the prongs will absorb movement due to the heaving of the floor.

In some installations, the center longitudinal frame member may not be necessary and, in some installations, the bottom frame member may be omitted for economic reasons. In the construction illustrated in FIGURES 9, 10 and 11, the prefabricated panels are constructed and stored in a desired place until they are ready for use thus reducing the cost of such panels.

The advantages of the present invention over cement masonry structures or closures commonly referred to as a cinder block closure are quite apparent.

The actual man-time used in the mine at the point of building the fire resistant closure is much less than when building out of cement masonry units. This is extremely important in an emergency when a closure

of this new type of construction could be put up and completed in a few hours, compared with a much longer time when building a cement masonry unit closure.

Anyone can put up a new type of closure while the construction of one out of cement masonry units requires that at least the person laying the blocks be a skilled mason.

There is no mortar to be mixed and no error to make in the proportions of cement, lime, sand, and water as in the cement masonry unit construction. The chemical foam can be obtained in portable spray containers, ready to use, with no mixing of ingredients.

Screen panels may be prefabricated outside the mine with unskilled labor, thus reducing the cost of building a closure. Prefabricated screen panels may be stock-piled where convenient to use. This is like building the wall in big pieces ahead of time, something that cannot be done with cement masonry units.

In an emergency, anchoring prongs are used to hold the closure in position, resulting in setting one up securely without waiting for mortar to dry, drilling holes, etc.

In removing a closure, a cement masonry unit closure is broken up, and the pieces are not re-usable, while with the new type of closure the panels are removable and the framework can be completely dismantled and re-used.

Parts of the framework on the new type of closure are built with adjustable connections to adapt it to different sizes and shapes of openings, while the cement masonry units must be cut to fit.

Any gaps along the edges of the framework of the new type of closure are readily closed by spraying with the foam, while the cement masonry units must be cut to fit, then mortar must be troweled into the openings.

This new type of closure may be used in any position, whereas one built of cement masonry units must be built in a vertical plane only.

Should a man become trapped on the foam side of a new type of closure, he can either pull a few stripping wires, loosen several panels and step through the closure, or he can cut the foam with a pocket knife along a screen panel joint and after loosening several panels, step through the closure to safety. With a cement masonry unit it is almost impossible to break through, especially with the cement and gravel type of blocks.

Should a man become trapped on the framework side of the closure he can, with a few well aimed kicks, break the bond between screen panels, separate them, and walk through the closure.

The new type of closure is fire resistant, both the foam and the steel. It will withstand a high temperature for quite some time. Some cinder blocks used in cement masonry unit construction contain enough coke and coal to ignite under ideal conditions.

Should the new type closure be damaged by high enough temperatures to destroy some of the foam, it can have a new coat of foam sprayed on again as soon as the immediate source of heat is removed. This cannot be done with cement masonry units since the heat causes a chemical reaction in the cement itself. In the lime of the mortar a calcination takes place when subjected to high temperatures. Dehydration of the cement and aggregate occurs which will cause spalling of the surface, thus destroying the blocks if it continues deep enough.

In the new type of closure, full strength is obtained within a few minutes after spraying on of the foam. In the cement masonry unit construction, full strength is not obtained until the mortar sets up completely, which sometimes takes as long as 24 to 36 hours.

In the event of an explosion, a cement masonry unit closure is destroyed. The new type of closure may be bent, torn, or otherwise damaged, but with a minimum of replacement parts can be re-erected, sprayed with foam, and back into use within a few hours.

If a floor heaves, a cement masonry unit closure will

break up. When the same floor heaves with a new type closure, it can bend, absorbing the pressure. If placed with the anchor prongs, the prongs will bend, absorbing most of the pressure from the heave. Cracks in the foam may be re-sprayed to render it airtight immediately.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. In a mine passageway a fire resistant closure comprising a frame, a plurality of prefabricated panels, each of said panels including a screen panel, a layer of foam resinous material thereon, said screen panel including a portion of one edge thereof free of plastic whereby the prefabricated panels are overlapped in relation to each other, and sealing foam plastic material sealing the juncture between the prefabricated panels.

2. The structure as defined in claim 1 wherein said foam plastic material is provided with a stripping wire embedded therein adjacent one edge of the screen panel for breaking the bond between adjacent panels, said frame including support means for the prefabricated panels adjacent the upper edge thereof.

3. The structure as defined in claim 2 wherein said support means includes an inwardly and upwardly struck hook-type lugs formed in the frame.

4. The structure as defined in claim 1 including a means for supporting the screen panel from said frame, said supporting means including a hook-like projection on the upper end of said frame whereby the screen panel may engage the hook-like projection and be detached therefrom.

5. The structure as defined in claim 1 wherein said frame is adjustable and includes peripheral members constructed of overlapping sections, the overlapping portions of said sections being provided with a plurality of apertures, and fastening means extending through selected apertures and securing the members in adjusted position.

6. The structure as defined in claim 5 wherein said fastening means is in the form of a bolt assembly.

7. The structure as defined in claim 5 wherein said fastening means is in the form of a headed fastener having a slot therein, and a wedge inserted into said slot for securing the members in adjusted position.

8. The structure as defined in claim 1 wherein stripping wires are embedded in the foam resin adjacent the screen panel for separating the foam plastic along the junctures between the screen panels to enable the screen panels to be dismantled from the frame.
